Primary Examiner — Abraham Bahta(74) *Attorney, Agent, or Firm* — Franklin & Associates International Inc.; Matthew F. Lambrinos(57) **CLAIM**

The ornamental design for a reusable envelope, as shown.

DESCRIPTION

The FIGURE is a front view of the reusable envelope showing my new design.

The reusable envelope with an applied design is interpreted to be flat and has no appreciable thickness.

1 Claim, 1 Drawing Sheet(56)
